George Cook

United States Patent Office.

GEORGE COOK, OF NEW HAVEN, CONNECTICUT.

Design No. 3,818, dated January 18, 1870.

DESIGN FOR AN ORGAN OR MELODEON-CASE.

The Schedule referred to in these Letters Patent and making part of the same.

To all whom it may concern:

Be it known that I, GEORGE COOK, of the city and county of New Haven, in the State of Connecticut, have invented a new and useful Improvement in Design for Organ or Melodeon-Cases; and I do hereby declare that the following is a full, clear, and exact description of the construction, character, and operation of the same, reference being had to the accompanying drawings, which make part of this specification, in which—

Figure 1 is perspective view of the main portion of the organ or melodeon-case, above the bellows, showing the general shape or configuration, to which the top, fig. 2, is attached, when used in that double form.

Figure 2 is a perspective view of the organ or melodeon-case, above the bellows.

My improvement consists in making the organ or melodeon-case of the form, shape, or configuration shown in the drawings.

What I claim as my invention, and desire to secure by Letters Patent, is—

The form, shape, or configuration of the organ or melodeon-case, when constructed in the shape herein described.

GEORGE COOK.
